E. H. MADERE

BABY GUARD

Filed Sept. 27, 1922

Patented July 24, 1923.

1,463,125

UNITED STATES PATENT OFFICE.

ERNEST HUBERT MADERE, OF HAHNVILLE, LOUISIANA, ASSIGNOR TO BIENVILLE MANUFACTURING COMPANY INC., OF NEW ORLEANS, LOUISIANA.

BABY GUARD.

Application filed September 27, 1922. Serial No. 590,827.

To all whom it may concern:

Be it known that I, ERNEST H. MADERE, a citizen of the United States, residing at Hahnville, in the parish of St. Charles and 5 State of Louisiana, have invented certain new and useful Improvements in Baby Guards; and I do hereby declare the following to be a full, clear, and exact description of the invention, such as will enable others 10 skilled in the art to which it appertains to make and use the same.

My present invention relates to improvements in devices for protecting young children against accidental injury to the head 15 or back during that period when they are learning to sit up and are liable to fall over sideways or backwards when attempting to sit up, with possible injury to the head or back from striking the same on the floor or 20 other platform on which they are seated.

It is a common expedient for mothers to put pillows or cushions at the sides and back of the child when it is learning to sit up to prevent it from injuring itself in the 25 manner referred to; and this device is intended to do away with the need of any such additional safeguards, and is so devised that it can be transported with the child from place to place without inconvenience either 30 to the nurse or to the child itself.

The invention is especially arranged to protect the child against falling backwards or sideways and bumping its head. In falling forwards the child will normally protect itself with its hands; moreover it is desirable to permit the child to bend over forwards so as to enable it to crawl or squirm about in the manner peculiar to infants at 35 the age referred to.

40 My invention will be more fully understood after reference to the accompanying drawings, in which like parts are indicated by similar reference symbols throughout the several views, and in which:—

45 Figure 1 is a perspective view showing the child in dotted lines seated on a floor, and showing the device in full lines.

Figure 2 is a perspective view of the device as detached from the child; and

50 Figure 3 is a detail view, partly in section, showing the device as extended.

A represents a belt or band which may be made of leather or textile fabric, such as canvas, cotton-duck or the like, which is 55 preferably wider at the center as at a, and

doubled over at its center as at a' to form a double thickness as at a''. One end is provided with a tongue a³, perforated as at a³, and the other end is provided with a loop a⁴ to which is secured the buckle B.

Secured between the folds of the double portion of the band are the metal plates C, which may be held in place in any convenient way, as by means of the stitches a⁵. These plates are preferably made of soft 60 flexible metal to which are attached in any convenient way, as by soldering, the resilient legs D, which diverge outwardly and downwardly, and are preferably bent, as at d, and terminate in feet E which may be made in 65 the form of metal balls, or preferably of rubber or other soft material to give a cushioning effect. These feet E not only serve to protect the floor or bed or other platform on 70 which the child is seated from accidental injury, but also prevent the nurse from having her clothes torn thereby, and also serve to make the device noiseless when used on a 75 hard floor.

It will be seen that the central leg projects rearwards and the two side legs project substantially at right angles to the central leg and cover the two sides of the child, while the band goes around the body of the child under the shoulders, and is buckled in 80 place, as shown in Fig. 1. It will thus be seen that when the child is sitting up, as shown in Fig. 1, it cannot fall backwards or sideways, but it may bend forwards and crawl along on its hands and knees in the 85 usual way. At that time the band is not in the way of the child, and the legs D project above the back of the child clear of the floor, bed or other platform on which the child is placed.

It will be seen that the device will thoroughly protect the child against injury from falling backwards or sideways, but will permit it to lean over forwards and crawl 90 freely if desired.

The device may be made durable to supply the needs of an increasing family, or the same may be made for rent if desired, as no one child would need the device for any great length of time during its growth; but when needed the device will be very efficient in service, a great comfort to the child itself, and a great relief to its mother or the nurse.

It will be obvious that the legs may be se- 110

cured in any convenient way, provided they are held in the divergent relation as shown. While three legs will ordinarily be sufficient for all practical purposes, the number of the 5 same may be increased if desired; and it will be obvious that various other modifications might be made in the herein described device, and in the construction, combination and arrangement of parts which could be 10 used without departing from the spirit of my invention; and I do not mean to limit the invention to such details except as particularly pointed out in the claims.

Having thus described my invention what 15 I claim and desire to secure by Letters Patent of the United States is:—

1. A protecting guard for young children, comprising a broad flexible adjustment band adapted to go around the body of the child

beneath the shoulders, and extending downwards from the shoulders and supporting the back and sides of the child, with a plurality of divergent resilient legs secured to and projecting downwards from said band at the sides and rear thereof. 20

2. A protecting guard for young children comprising a band adapted to go around the body of the child, said band being doubled along its center, flexible metal plates secured between the folds of said band, divergent resilient rods secured to said plates and projecting downwards from said band, and a foot attached to the free end of each rod adapted to engage the platform on which the child may be seated, substantially as and for 30 35 the purpose described.

ERNEST HUBERT MADERE.
